PLASTERBOARD REINFORCEMENT

Robert J. Sterling, Chicago, Ill., assignor to
 United States Gypsum Company, Chicago, Ill.,
 a corporation of Illinois

Application December 10, 1934, Serial No. 756,774

6 Claims. (Cl. 72—124)

This invention relates to building constructions and devices, and has reference more particularly to building constructions in which joint reinforcing material is movably attached to plaster or other building boards.

In the construction of walls, it is common to nail plaster boards, fiber boards, or other building boards to wooden studs or joists, or to secure said boards to steel framework by means of clips.

10 Plaster is then applied to exposed faces of the boards as a base for a decorative coating, such as plastic paint or wall paper. It is desirable to reinforce the joints at the abutting edges of the boards, so that cracks will not form in the plaster 15 and decorative coating.

An object of this invention, therefore, is to provide a reinforcing element loosely attached to the board at the time of shipment so that said reinforcing element may be moved into operative 20 position at the time the wall or ceiling is erected to receive the plaster surface coat; also to improve building constructions in other respects hereinafter specified and claimed.

Reference is to be had to the accompanying 25 drawing forming a part of this specification, in which

Fig. 1 is a sectional elevation of a wall constructed in the improved manner with parts broken away to disclose the construction,

30 Fig. 2 is an elevation of one of the clips for attaching the reinforcing element to the boards prior to shipment, and

Fig. 3 is a sectional view on a large scale through the edge of a board showing the reinforcing element in shipping position.

Referring to the drawing by numerals, studs 10 and joists 11 form the framework of a room or building. Boards 12 are attached to the frame members 10 and 11 by means of nails 13 with 40 their edges in abutting relation. The boards 12 may consist of a plaster core 14 having paper cover sheets 15, or said boards may consist of vegetable fibers or other desired material. To 45 one or more edges of each board 12, a reinforcing element 16 is loosely attached, said element consisting of a strip of expanded metal, wire mesh or other suitable material. The reinforcing element 16 is movably and slidably attached to the board edge by means of a spring wire clip 50 17 having a detent 18 at the outer end which presses against the reinforcing element 16 and holds it in shipping position with the outer edge of the element preferably positioned somewhat inside the edge of the board. The inner end of 55 clip 17 is bent laterally to form a transversely

extending section 19 which in turn is bent to form a section 20 which extends longitudinally of the clip 17. The section 20 is return bent to form a section 21 which terminates in outwardly extending pointed prong 22, the latter being forced through the board 12 prior to shipment. The end 23 of prong 22 is bent or clinched laterally against the back of board 12 so as to firmly seat the section 19 against the front face of the board, said section 19 serving to stabilize the clip 17 and prevent any tendency to tip. At the time of shipment and during erection of the boards, the reinforcing strip 16 will be held in from the edge of the board by clip 17 as shown at the left hand of Fig. 1. The workman then moves the strip 16 to extend over the board joint as seen at the right hand of Fig. 1. A coating of plaster 24 is then applied over the exposed faces of the boards 12 and strips 16 in the usual manner. After the plaster has set and dried, a decorative coating 10 of plastic paint, wall paper, etc., is applied to the exposed face of the plaster.

I would state in conclusion that while the illustrated example constitutes a practical embodiment of my invention, I do not wish to limit myself precisely to these details, since manifestly the same may be considerably varied without departing from the spirit of the invention as defined in the appended claims.

Having thus described my invention, I claim 30 as new and desire to secure by Letters Patent:—

1. An article of manufacture comprising a building board, a strip of expanded metal reinforcement slidably positioned along an edge of said board, and means for removably securing 35 said strip to a face of said board.

2. An article of manufacture comprising a building board, a strip of reinforcing material slidably positioned along an edge of said board, and a spring clip attached to said board and 40 adapted to removably secure said strip to a face of said board.

3. An article of manufacture comprising a building board, a strip of expanded metal joint reinforcement slidably positioned along an edge 45 of said board, a spring wire clip having a prong adjacent one end and extending through said board, the end of said prong being clinched against one face of said board, and a detent formed on the opposite end of said clip and adapted to bear against said strip and removably secure said strip to a face of said board.

4. An article as described in claim 3 characterized by a flat section on said clip adapted to bear 50

against the face of said board so as to stabilize said clip to prevent tipping thereof.

5. In a building construction, a stud, a pair of boards secured to said stud with edges abutting, and a reenforcing strip of expanded metal slidably secured to one of said boards and adapted to overlie the joint between said boards, the exposed faces of said boards and strip being adapted to receive a coating of plaster.

6. A spring wire clip suitable for the slidable attachment of reenforcing strip to a building board, comprising a wire clip body, an outstanding prong formed between the ends of said body, and a detent adjacent one end of said body for 5 yieldingly engaging said strip.

ROBERT J. STERLING.
